UNITED STATES PATENT OFFICE

2,569,552

WIRE CLOTHESPIN

William H. Bridwell, Tulsa, Okla.

Application December 5, 1945, Serial No. 632,912

1 Claim. (Cl. 24—139)

1

My invention relates to a new and useful improvement in a fastening device adapted for use particularly in fastening articles on a support. The invention is particularly adapted for use in fastening clothes on a clothes line or for similar purposes where the article is folded over the support so that the fastening device may clamp the article in position on the support.

It is an object of the present invention to provide a fastening device of this class which will be simple in structure, economical of manufacture, durable, compact, highly efficient in use, easily applied and so constructed and arranged that a tearing of the fabric will be avoided.

Another object of the invention is the provision of a fastening device which when in position will have an attractive appearance.

Another object of the invention is the provision of a fastening device having a body formed from wire coiled into a resilient coil and so arranged and constructed that the coil may be spread apart and serve to clamp the article upon the support.

Another object of the invention is the provision of a fastening device formed from a single piece of wire coiled upon itself to provide a resilient coil and having positioned on one of the coils and lying between the opposed ends a gripping member.

Other objects will appear hereinafter.

It is recognized that various modifications and changes may be made in the detail of structure illustrated without departing from the invention and it is intended that such variations and modifications shall be embraced within the claim which forms a part hereof.

Forming a part of this specification are drawings in which,

Fig. 1 is a perspective view of the invention,

Fig. 2 is a side elevational view of the invention showing it applied in use.

Fig. 3 is a sectional view taken on line 3—3 of Fig. 1.

Fig. 4 is a sectional view taken on line 4—4 of Fig. 1.

Fig. 5 is a perspective view of a slight modification of the invention,

Fig. 6 is a sectional view taken on line 6—6 of Fig. 5.

In Fig. 5, I have illustrated a wire coiled upon itself to provide the central coil 8 and the exterior or terminal coils 9 and 10. In Fig. 1 and Fig. 3, I have indicated a finger grip 11 mounted on the central coil 8 and provided with a bore 12 through which the coil 8 is extended. The end faces of the coils 9 and 10 terminate in slightly spaced relation to the side faces of the member 11 as clearly shown in Fig. 3. The wire is of a resilient type so that the coil is a spring coil.

While the invention is adapted for use in fastening generally I have, in Fig. 2, illustrated the

2

invention used for fastening a fabric 13 in folded-over relation on a clothesline 14. The device is inserted on the line so that coils are spread apart and the clothesline and the fabric 13 are engaged between a pair of adjacent coils. When mounting the device in position the operator would hold the device by the gripping member 11 so that the lower ends of the coils would be closed and slip over the line 14 and the fabric 13 without endangering a tearing of the fabric. Experience has shown that when the garment fastener is mounted on the line the coils are slightly distorted and the end faces of the coils 9 and 10 may approach more closely to the gripping member 11. It is for these reasons that the clearance or space clearly shown in Fig. 3 is provided. Furthermore, experience has shown that change of temperature may effect expansion or contraction of the coil members and construction is such that this expansion and contraction may take place.

The member 11 may be made of wood, plastic material or a suitable material. It may also be brilliantly colored so that when it is mounted on the line a pleasing appearance is presented. It is believed obvious that the device is compact and may be stored away in quantities in a small space and that it is also light and durable.

What I claim as new is:

30 A fastening device of the class described comprising: a body formed from a single piece of resilient wire coiled upon itself to provide a coil, the ends of said wire being extended at opposite sides of said coil to provide a portion of a coil at each side of the coil; and a gripping member 25 having a passage formed therethrough, said coil extending through said passage and rotatable thereon, and the opposed end faces of the ends of said wire being positioned adjacent to and in spaced relation to the end face of said gripping member.

WILLIAM H. BRIDWELL.
